UNITED STATES PATENT OFFICE.

JOHN M. WALSH, OF PETALUMA, CALIFORNIA.

STREET-SEMAPHORE.

1,384,365.

Specification of Letters Patent. Patented July 12, 1921.

Application filed April 16, 1919. Serial No. 290,527.

To all whom it may concern:

Be it known that I, JOHN M. WALSH, a citizen of the United States, and a resident of Petaluma, county of Sonoma, State of California, have invented a new and useful Street-Semaphore, of which the following is a specification.

My invention relates to street signals for the guidance and regulation of traffic.

10 An object of my invention is to provide a portable semaphore for the direction of traffic which may be placed upon the pavement of the street at the desired location and which may be moved out of the way during 15 the rain, or at other times when desired.

Another object of my invention is to provide a semaphore yieldingly held so that when struck accidentally it gives way, but immediately after the contact reassumes its 20 first position.

Another object of my invention is to provide a semaphore of the character described which is nearly indestructible and certain of 25 proper operation under all conditions which may surround its use.

The invention possesses other objects and 30 features of advantage, some of which, with the foregoing, will be set forth in the following description of the preferred form of my invention which is illustrated in the drawings accompanying and forming part of the specification. It is to be understood that I do not limit myself to the showing made by the said drawings and description as I may 35 adopt variations of the preferred form within the scope of my invention as set forth in the claims.

Referring to the drawings:

Figure 1 is a vertical sectional view 40 through my semaphore.

Fig. 2 is a horizontal sectional view taken in the plane 2—2 of Fig. 1.

Fig. 3 is an elevation on a smaller scale of the semaphore.

45 My complete semaphore consists of a signal supported upon a standard, the standard being yieldingly held in an upright position upon a broad base.

50 My semaphore is mounted upon a flat base plate 6 preferably circular in form and with rounded thin edges. The base is of sufficient weight and diameter to give stability to the semaphore and short pointed projections 7 are formed upon the under side of the base 55 to prevent side slipping when the apparatus is struck by a vehicle.

Upon the base plate rests the ball 8 which carries the hollow standard 9 upon which the signal 11 is mounted. The ball is preferably of solid metal and quite heavy, and 60 is flat on one side, leaving a lug 12 projecting therefrom. The flattened area of the ball rests upon the base plate, the lug 12 projecting into a conically formed recess 13 in the center of the base. The relative shapes and 65 sizes of the lug and recess are such that if the ball is tipped over upon its side by contact with a vehicle, in the recovery movement the lug engages the sides of the aperture and insures a proper seating of the ball 70 in the position shown in Fig. 1. The lug also serves to prevent lateral displacement of the ball upon the base.

Means are provided for insuring the recovery movement of the ball and standard to an 75 upright position after being displaced therefrom by being struck for any reason by a passing vehicle or animal:

Arranged in the hollow standard 9 is a coil spring 14 confined between the shoulder 80 16 formed at the bottom of the socket in which the standard 9 is held, and a plate 17 adjustably held upon the tension rod 18 by the nut 19. The tension rod extends through the spring to a point near the 85 shoulder 16, where it connects to a chain 21 the other end of which is secured to an eye bolt 22 seated in the bottom face of the base 6. The spring is under compression 90 which is increased by tipping of the ball, and it therefore quickly returns the ball and standard to upright position after they have been knocked over.

Rotatably arranged on the hollow standard above the ball is a signal comprising a 95 cylindrical casing 11. The lower end of the casing is reduced in diameter to seat about the standard immediately above the ball and the upper end is provided with a threaded cover plate 24 apertured at its center to 100 surround the standard. A cap 26 threaded to the standard, retains the casing 11 upon the standard. Preferably the signal casing is rotatable upon the standard so that when the semaphore is struck a glancing blow, it 105 will turn in the direction of the blow.

The casing is apertured at various points in its lateral wall and red, light reflecting devices 27 mounted on the ends of resilient flat strips 28 secured to the inside of the 110 casing, extend through the apertures. The resilient mounting of the reflectors permits

them to be pressed backwardly within the casing, if struck, so that injury is avoided.

Upon the outside of the signal casing directions to guide the flow of traffic are 5 prominently arranged. Fig. 3 shows a semaphore upon which the words "to right" appear in a vertical line on the casing. Such words are printed in large characters and appear at intervals about the casing so 10 that they are always visible to the drivers of approaching vehicles.

I claim:

1. A semaphore for street traffic having a flat base, a ball tilttable upon the base, a 15 rigid hollow standard secured in and extending up from the ball, a spring in said standard seated in said ball, and means connected to the base for holding it upon the seat in the ball and operative to further compress 20 the spring when the standard is tilted with the ball so that the standard is normally maintained upright.

2. A semaphore for street traffic having a flat base with a central socket, a ball tilt- 25 able upon the base and having a lug matching in the recess, a rigid hollow standard secured in and extending up from the ball, a

spring compressed in said standard, and seated in the ball and means connected to the base and operative to further compress 30 the spring when the standard is tilted with the ball so that the standard is normally maintained upright.

3. A semaphore for street traffic having a base with a central aperture and recess, a 35 ball having a flat face seating on the base and having a centering lug entering the recess, a hollow standard extending from the ball, a flexible device in the aperture of the base and passing through the ball and into 40 the standard, a rod attached to said device and having a plate slidably fitting the standard, and a spring seated in the ball and compressed in the standard between the plate and said ball by said device and rod to 45 maintain the standard upright and the ball seated flat on the base.

In testimony whereof, I have hereunto set my hand at Petaluma, California, this 7th day of April, 1919.

JOHN M. WALSH.

In presence of—

W. T. MOONEY,
OU SMITH FEVILLEA.
